UNITED STATES PATENT OFFICE.

HENRY W. HENNEBERG, OF CHICAGO, ILLINOIS.

CLOTHES WRINGER.

Application filed August 28, 1919. Serial No. 320,337.

To all whom it may concern:

Be it known that I, HENRY W. HENNEBERG, citizen of the United States, residing at Chicago, in the county of Cook and State 5 of Illinois, have invented certain new and useful Improvements in Clothes Wringers; and I do hereby declare the following to be a full, clear, and exact description of the invention, such as will enable others skilled 10 in the art to which it appertains to make and use the same.

This invention relates to improvements in clothes wringers and particularly power actuated clothes wringers, and has for its object 15 to provide means for readily and instantaneously effecting separation of the wringer rolls and throwing the gears transmitting power from one roll to the other out of mesh with each other in the event that the 20 operator has his or her fingers caught between the rolls in feeding the wringer.

A further object of the invention is to provide means whereby the spring or springs exerting a pressure whereby one of the rolls 25 is forced toward the other thereof, is utilized as the means for effecting instant separation of the rolls in the event aforesaid.

The invention consists in the features of construction and combinations of parts hereinafter fully described and particularly 30 claimed.

In the accompanying drawings illustrating a suitable embodiment of the invention;

Figure 1 is a front elevation of a wringer 35 constructed in accordance with the invention, a part thereof being broken away.

Figure 2 is a side elevation of the same.

Figure 3 is a fragmentary detail plan section thereof on the line 3—3 of Figure 1.

Figure 4 is a vertical transverse section of the same on the line 4—4 of Figure 1.

Figure 5 is a detail vertical section on the line 5—5 of Figure 2.

The clothes wringer, which may be of any 45 of the standard types generally used in the household, consists of a frame comprising the side rails 1 equipped at their lower ends with means for engaging the same with the rim of a wash-tub, or other suitable 50 support, and which are connected together by means of cross pieces 2, 3 and 4 at convenient intervals.

Rigidly mounted in the lower end portion of the side rails are the bearings 5 for the 55 shaft 6 of the driven roll 7, the latter being geared to the companion roll 8 by means of

mesh spur gears 9 and 10 in a well known manner. The shaft 11 of the companion roll is journaled in bearings 12 in the side rails 1 and said bearings are vertically movable 60 in suitable guides in said side rails. In the instance illustrated, two helical compression springs 13, which are associated with the thumb screws 4 in a well known manner, bear upon the bearings 12 to maintain the 65 roll 8 pressed against the roll 7 and the gears 9 and 10 in mesh with each other. It will be obvious, of course, that the exact character and number of the springs used are wholly immaterial and vary in different 70 wringers to which the present invention is applicable.

According to my invention the side rails 1 are transversely cut substantially midway between their upper and lower ends, and 75 more particularly between the axes of rotation of the rolls 7 and 8, the said respective parts of said side rails being connected together by means of hinges 15, the pivots of which preferably project considerably rearwardly of the rear faces of said side rails whereby, when the respective parts turn on said hinge pivots as a center, the separation of the rolls become greater and sufficient to instantly relieve any pressure on fingers 85 caught between the rolls. The upper leaf of each of the hinges is preferably provided with a horizontal flange shown in Figure 5, which constitutes a stop for the bearing of the shaft of the roll 8 when the frame parts 90 are separated, as indicated in dotted lines in Figure 2, and the springs engaging the bearings of said roller force them inwardly and against said flanges. Pivoted to the forward ends of the upper leaves of the hinges 15 are 95 the two arms 16 of an inverted U-shaped lever, the said pivotal connections being made between the ends and adjacent the lower ends of said arms. Each of the latter is provided in its rear edge with a recess 17 in 100 which a pin 18 on the lower leaf of each of the hinges 15 is adapted to be engaged, the lower face of the recess 17 being arcuate on the pivot of the lever as a center, or substantially so. The radius of curvature of this wall of the recess is preferably very slightly decreased toward the mouth of the recess so that the tension exerted on said arms will tend to maintain the pin 18 more firmly engaged in said recess. The upper or middle 110 portion of the U-shaped lever is preferably disposed at an elevation slightly above the

upper cross piece 2 to allow sufficient free space to cause said lever to turn freely and rapidly through a very short arc upon receiving a blow from the hand for the purpose of releasing the rollers 7 and 8 from engagement with each other and throwing the gears 9 and 10 out of mesh. The rigidity of the inverted lever 16 is such that a blow administered upon any part thereof above its pivotal connections with the hinges 15 will serve to throw the arms 16 simultaneously out of engagement with the pins 18.

In operation it is customary for the person operating the wringer to feed the same generally with one hand disposed to guide clothes to the wringer rolls and the other thereof further away from the same to spread the clothes to prevent bunching thereof in the rolls and to prevent buttons from becoming transversely disposed to the direction of motion of the clothes. Thus the danger of the hand being caught in the wringer is usually limited to that hand which is normally disposed in close proximity to the wringer rolls thus leaving one hand free. In the event that the fingers of one hand should become caught between wringer rolls the operator may instantly administer a blow with the other hand to any part of the releasing lever whereupon pressure exerted by the springs 13 will cause the frame to open, as indicated in dotted lines in Figure 2 thus instantly separating the rolls 7 and 8 from each other and throwing the spur gears 9 and 10 out of mesh.

When it is desired to again position the wringer parts, as shown in full lines in Figures 1 and 2 it is necessary for the operator to first manipulate the thumb screws 14 to release the pressure on the springs 13 and bearings of the roll 8 and then return the upper part of the frame to its normal position, and to thereupon manipulate the thumb screws to cause the springs 13 to bear upon the bearings of the roll 8 with any desired degree of pressure.

While I have illustrated a suitable embodiment of the invention in the accompanying drawings, it will be obvious, of course, that such embodiment may be changed and varied in details of construction to adapt the device to various types and sizes of wringers, and to accomplish the desired results without departing from the invention as defined in the appended claims.

I claim as my invention:

1. A clothes wringer comprising a frame consisting of a part adapted for rigid support and carrying a driven wringer roll, and

a part carrying a spring pressed wringer roll, said parts hinged together, the spring pressure tending to separate the two parts and to place them in an angularly disposed relation to each other, latch elements rigid with and disposed at opposite sides of the first mentioned part of the frame, a U-shaped lever pivotally secured between the ends of its arms to the other part of the frame and provided at the free ends of its arms with means for engaging said latch elements to hold said frame parts in vertical alignment and said spring pressed roll bearing upon the driven roll, the middle part of said forked lever disposed above the elevation of the uppermost of said rolls and at the receiving side of the wringer frame and adapted when moved toward the wringer frame to release the latch elements.

2. A clothes wringer comprising a frame consisting of a part adapted for rigid support and carrying a wringer roll, and a part carrying a spring pressed wringer roll, said parts being hinged together, the spring pressure tending to separate the two parts and to place them in an angularly disposed relation to each other, keepers rigid with and disposed at opposite sides of the first mentioned part of the frame, latches pivotally secured to the movable part of the frame and engageable with said keepers for holding said frame parts in vertical alignment and said spring pressed roll bearing upon the other roll, an actuating element connected with said latches and extending above the uppermost roll at the receiving side of the wringer and adapted, when moved toward the wringer, to release the latches from said keepers.

3. A clothes wringer comprising a frame consisting of a part adapted for rigid support and carrying a wringer roll, and a part carrying a spring pressed wringer roll, said parts being hinged together, the spring pressure tending to separate the two parts and to place them in an angularly disposed relation to each other, keepers rigid with and disposed at opposite sides of the first mentioned part of the frame, latches pivotally secured to the movable part of the frame and engageable with said keepers for holding said frame parts in vertical alignment and said spring pressed roll bearing upon the other roll, an actuating element connected with said latches and extending above the uppermost roll of the wringer and adapted to be swung in a vertical plane to release the latches.

HENRY W. HENNEBERG.
